HENRY A. FRAMBURG, OF CHICAGO, ILLINOIS, ASSIGNOR TO H. A. FRAMBURG & COMPANY, OF CHICAGO, ILLINOIS.

ELECTRIC LAMP.

Application filed November 27, 1923. Serial No. 677,203.

To all whom it may concern:

Be it known that I, HENRY A. FRAMBURG, a citizen of the United States, residing at Chicago, in the county of Cook, State of Illinois, have invented certain new and useful Improvements in Electric Lamps, of which the following is a description, reference being had to the accompanying drawing, and to the figures of reference marked 10 thereon.

This invention relates to an electric lamp unit in which the light bulb is enclosed within an outer globe and the bulb socket is mounted within a casing which carries the 15 globe, the parts being so constructed and arranged that the globe may be readily removed for the purpose of replacing the bulb or bulbs enclosed within.

It has been the general practice in the past 20 to use screws for holding the globes or shades or the equivalent glassware to the holder, but such an arrangement has been a troublesome one for the reason that in setting up the screws to hold the shades or 25 globes, undue pressure is applied to the rim thereof with a consequent breaking; hence if breakage does not occur at time of putting globe in place, it may occur later due to 30 expansion by heat. Furthermore by the use of screws the globes or shades are rarely ever centralized with respect to the bulb.

Where lamp bulbs are enclosed in a globe the light which passes through the globe comes directly from the filament of the bulb 35 and part of this is absorbed in the globe.

It is one of the prime objects of my invention to provide a lamp in which the light rays which ordinarily pass upward are reflected downward, thereby adding to the 40 light emanating through the globe.

A further object of my invention is to provide an arrangement in which the globe is held substantially all the way around its periphery by a holding ring, thereby eliminating undue pressure at any point as is 45 obtained by the use of screws.

While attaining the object last described, it is a further object to provide means whereby the globe may be easily and quickly 50 removed for cleaning purposes or for the purpose of changing or removing the lamp bulb.

A still further object is to provide a lamp which may be readily connected up to a

lighting circuit; also one in which the heat 55 generated by the lamp bulb may be easily dissipated without leaving openings for bugs and insects to get inside the lamp.

These and other objects will be apparent to those skilled in the art after a study 60 of the specification taken in connection with the annexed drawing, wherein:

Figure 1 is a part elevational and part sectional view of the lamp, but with the lower part of the globe broken away. 65

Figure 2 is a view on a considerably reduced scale of the bottom of the lamp, without the globe.

Figure 3 is a fragmentary view of a portion of the casing showing the way of locking 70 two parts of the casing together.

Figure 4 is a fragmentary sectional view showing a modified form of a locking means to be used in place of that shown in Fig. 3. 75

In the drawings 1 illustrates a base, preferably of metal, which is formed with an annular lip 24, which has two portions 18 and 19 cut away at points substantially diametrically opposite for the purpose which shall be later referred to. On the 80 base 1 is carried a bracket 2, the same being fastened thereto in any satisfactory manner, such as by screws 10. The base 1 also carries a lamp socket 9, the same being fastened thereto by screws 11. Supported on 85 the top part of the bracket is a bell-shaped member 4, which acts as a support for what may be termed a ring member 3. The member 4 has an annular rim 23, which carries the ring 3. The upper edge of the ring 90

3 has notches 14, three of which are found to be satisfactory for the purpose. Punched out of the material of the member 4 are lugs 13, which are adapted to allow the notches 14 to pass over, after which the 95 ring 3 is turned to the position shown in Fig. 3, thereby locking the ring in position on the rim 23. The ring 3 has a downwardly projecting flange 25 that is adapted to fit downwardly over the lip 24 on the base 1 encompassing the rim 17 on the globe 12, thereby peripherally engaging the globe and holding it in position. The inner line of the rim 17 is shown in Fig. 2 by a dotted line. 100

Should it be necessary to clean the globe or to change the bulb in the socket 9, the ring 3 is turned until the notches 14 are 105

in line with the lugs 13 when the ring member 3 may be raised and the globe tilted so that it will pass over the cut-away portions 18 and 19 of the base 1, which cut-away portions therefore act as means for passing the globe over or withdrawing it from the base 1. In place of the punched up lugs 13 on the member 4, screws may be set into the member 4 and perform the same functions as the lugs 13, all as shown in Fig. 4.

Attached to the bracket 2 is a member 6 preferably threaded so as to be screwed into the bracket 2 and a nut 8 is used to clamp the member 4 on to the bracket and at the same time lock the member 6 in place. Passing over the upper end of the member 4 is a dome member 5 so shaped that the rounded portion 16 covers a series of holes 15 in the upper part of the bell-shaped member 4. The holes 15 cooperate with the holes 20 in the base 1 to allow the heated air within the globe to pass upward through the holes 15 to the outer air by way of the space 16 and the annular space 26. The holder 7 is screw threaded on to the member 6 clamping against the dome 5 to hold it in position on the member 4. The member 6 is hollow as indicated by the passageway 21 for the purpose of allowing the conductors to be carried to the lamp socket.

I prefer to construct the base member 1 so that it will act as a reflector for throwing downward the light rays, coming to its surface from the lamp bulb. I have found that this arrangement materially increases the efficiency of the entire device.

From what has been said, it will be readily perceived that the device herein described is one that can be easily manufactured and quickly assembled and disassembled all for the purposes set forth.

While I have shown the preferred form of one embodiment of my invention, I do not wish to be limited to the exact details shown and described, as it will be apparent that these details may be varied over quite wide limits.

Having thus described my invention, what I claim is:

1. In a device of the class described; in combination, a base carrying a lamp socket, a bracket attached to said base, a ring supporting member carried by the bracket, a ring supported by said member, a globe held in position on said base by said ring, and means attached to the bracket for supporting the entire device.

2. In a device of the class described; in combination, a base carrying a lamp socket, a bracket attached to said base, a ring supporting member carried by the bracket, a ring supported by said member, a globe held in position on said base by said ring, a dome fitting over said ring supporting

member, a member attached to said bracket and extending upward through the dome and a holder attached to the last mentioned member.

3. In a device of the class described; in combination, a base carrying a lamp socket, a bracket attached to said base, a ring supporting member carried by the bracket, a ring supported by said member, a globe held in position on said base by said ring, a dome fitting over and resting on said ring supporting member, a threaded member attached to said bracket and extending upward through the dome, a nut on the threaded member to clamp the ring supporting member to the bracket and a holder having a threaded part to engage said threaded member to hold said dome in position.

4. In a device of the class described; in combination, a base carrying a lamp socket, a bracket attached to said base, a ring supporting member carried by the bracket, a ring supported by said member, said member and ring having means for detachably locking said parts together in operative position, a globe held in position on said base by said ring, means associated with said base for permitting the globe to be placed over its outer periphery and means attached to the bracket for supporting the entire device.

5. In a device of the class described; in combination, a base carrying a lamp socket, a bracket attached to said base, said base having an extended lip with diametrically opposite portions removed therefrom, a ring supporting member carried by the member, a ring supported by said member, a globe having a rim smaller in diameter than the diameter of the lip on said base, but adapted to pass over the cut-away portions of said lip and to rest on said lip, said ring having a flange adapted to pass over the rim of said globe and hold the same in position on said base lip, a dome resting on said ring supporting member, a member attached to said bracket and extending upward through said dome and a holder attached to said last mentioned member.

6. In a device of the class described; in combination, a base having an annular lip, a lamp bulb socket and a bracket attached to said base, a ring supporting member carried by the bracket, a ring carried by said member, said ring having a flange adapted to cooperate with said lip for clamping the globe over said bulb, ventilating holes in said base and in the upper part of said ring supporting member, a dome resting on said ring supporting member having a part extending below the ventilating holes in said member, and a holder having a stem extending through the dome and attached to said bracket.

7. In a device of the class described; in

- combination, a base carrying a lamp socket, bracket attached to said base, a ring supporting member carried by the bracket, a globe held in position on said base by said 5 ring, said base and ring supporting member having ventilating holes, a dome seated in the ring supporting member having a part extending downward over the said member forming an air chamber with an annular air 10 opening thereinto, a holder having a stem passing through the dome and attached to said bracket.
8. In a device of the class described; in combination, a base carrying a lamp socket, 15 a bracket attached to said base, a ring supporting member carried by the bracket, a ring detachably carried by said member, a globe held in position on said base by said ring, a holder having an extension attached 20 to said bracket, and a dome member held in position on the ring supporting member by said holder and stem, said base further acting as a reflector.
9. In a device of the class described, a 25 base carrying a lamp socket, a bracket attached to said base on one side, said base being finished on the other side to act as a reflector, a ring supporting member carried by the bracket, a ring supported by said 30 member, a globe held in position on said base by said ring and means attached to the bracket for supporting the entire device.
10. In a device of the class described, a 35 base formed with an annular lip to support a globe and having a lamp socket and bracket attached on one side thereof, with its other side finished to act as a reflector, a ring member having a portion formed to clamp said globe over the lip on the base, 40 means for supporting the ring, and means attached to the bracket for supporting the entire device.
11. In a device of the class described, a 45 base formed with an annular lip to support a globe and having a lamp socket and a bracket attached on one side thereof, with its other side finished to act as a reflector, said base having ventilating holes therein, a ring member having a portion formed to clamp 50 said globe over the lip on the base, a bell-shaped member carried by said bracket for detachably supporting said ring, said member having a series of ventilating holes in its upper portion, a dome member supported 55 on said bell-shaped member having a portion forming an air chamber over said ventilating holes therein, and a holder having a stem passing through the dome and attached to said bracket for supporting the 60 entire device.
12. In a device of the class described, a 65 base for supporting a globe, a globe having a flanged opening smaller in diameter than the nominal diameter of the base, said base having cut-away portions whereby the globe 70 can be tilted and passed over the outer periphery of the base, a lamp socket carried by the base, a ring member for clamping the globe to the base, means independent of the base for supporting the ring member, and means for supporting the entire device.
13. In a device of the class described, a 75 base for supporting a globe, a globe having a flanged opening smaller in diameter than the nominal diameter of the base, said base having cut-away portions whereby the globe can be tilted and passed over the outer periphery of the base, a lamp socket carried by the base, a ring member for clamping the globe to the base, a member for detachably 80 supporting the ring, a support attached to the base for the last mentioned member and a holder for the entire device having attachment means to the support attached to said base.
14. In a device of the class described, a 85 combined base and reflector having an annular lip for supporting a globe, a globe having a flange to rest on said lip with means associated with the lip to permit the globe to be passed over it, a ring for retaining the globe on the lip, a lamp socket on the base, a support for said base, a member carried by the support for carrying said ring and a holder for the entire device attached to said base support member.
15. In a device of the class described, a 90 member having one side finished to act as a reflector, a lamp socket mounted on the opposite side of said member but having the lamp opening toward the reflector side, a globe adapted to be supported around its periphery on said member with means associated with the member to permit the globe to be fitted over the said member, a ring for 95 retaining the globe on the member, a support on said member extending upward, a member attached to said support for carrying said ring and a holder for the entire device attached to said support.
16. In a device of the class described, a 100 member finished on one side to act as a reflector, a lamp socket and a support member attached to said reflector member, a globe supported around the periphery of the member, a ring for retaining the globe in position on the reflector member, a member carried by said support for carrying said ring, said ring and its support member having associated means for quickly disengaging the 105 ring from its operative position and a holder for the entire device attached to said support.
17. In a unit light, the combination with 110 a member carrying a lamp socket and acting as a reflector, of a globe peripherally supported on said member, a ring member for holding the globe in place on the reflector member, a holder for hanging the unit with means for attaching the holder to the 115 120 125 130

reflector member, and a support member for the ring member held in place by said attaching means.

18. In a unit light, the combination with 5 a member carrying a lamp socket and acting as a reflector, of a globe peripherally supported on said member, a ring member for holding the globe in place on the reflector member, a holder for hanging the unit with 10 means for attaching the holder to the reflector member including a bracket fastened to the reflector member and a threaded member between the holder and bracket, a support member for the ring member carried 15 on said bracket, and a dome member resting on said support member and enclosing said threaded member.

19. In a unit light including a base carrying a lamp socket on one side and a lamp 20 on the other, a globe for enclosing the lamp supported on said base, a ring for holding the globe in position, a bracket on the base, a

member carried by the bracket for supporting the ring member, a holder for the unit attached to said bracket and means for ventilating the unit; comprising holes in the base, holes in the ring supporting member, and a dome member resting on the ring support member and having a part extending over the holes therein and having an air 25 30 chamber having an annular outlet around the ring supporting member.

20. In a device of the class described, a base carrying a lamp socket, a support bracket attached to the base, a globe having 35 a rim fitting directly around and outside the outer edge of said base, and a ring having supporting means on the bracket for engaging the outer part of said globe rim to hold it in place on the rim of said base. 40

In testimony whereof, I affix my signature.

HENRY A. FRAMBURG.
